Primary Examiner — Catherine Ho(74) *Attorney, Agent, or Firm* — Quarles & Brady LLP;
Michael J. Curley(57) **CLAIM**

The ornamental design for a label, as shown and described.

DESCRIPTION

FIG. 1 is a front elevational view of the first embodiment for a label;

FIG. 2 is a front elevational view of the second embodiment for a label;

FIG. 3 is a front elevational view of the third embodiment for a label; and,

FIG. 4 is a front elevational view of the fourth embodiment for a label.

The dash-dash-dash lines illustrate portions of the label that form no part of the claimed design. The stippling represents a contrast in appearance.
